United States Patent [19]

Yung-Mao

[11] Patent Number: Des. 315,634

[45] Date of Patent: ** Mar. 26, 1991

[54] MIDSOLE WITH BOTTOM PROJECTIONS

[75] Inventor: Lin Yung-Mao, Taichung City, China

[73] Assignee: Autry Industries, Inc., Dallas, Tex.

[**] Term: 14 Years

[21] Appl. No.: 236,136

[22] Filed: Aug. 25, 1988

Related U.S. Application Data

[62] Division of Ser. No. 51,995, May 18, 1987, Pat. No. Des. 298,583.

[52] U.S. Cl. D2/318

[58] Field of Search ..... D2/264, 265, 274, 305-314, D2/317-321, 270, 293; 36/25 R, 28, 29, 32 R, 43, 59 R, 59 C, 11.5

CLAIM

The ornamental design for a midsole with bottom projections, as shown and described.

DESCRIPTION

FIG. 1 is a bottom perspective view of a midsole with bottom projections showing my new design;

FIG. 2 is a bottom plan view thereof;

FIG. 3 is a top plan view thereof; and

FIG. 4 is a left side elevational view thereof.
